United States Patent Office

Des. 189,531
Patented Jan. 3, 1961

189,531

FENDER FOR AN AUTOMOBILE

Robert C. Siebert, Roseville, Mich., assignor to Chrysler Corporation, Highland Park, Mich., a corporation of Delaware

Filed May 2, 1960, Ser. No. 60,417

Term of patent 7 years

(Cl. D14—6)

Fig. 1 is a side elevational view of a fender for an automobile showing my new design;

Fig. 2 is a top plan view thereof;

Fig. 3 is a front elevational view;

Figs. 4, 5, 6 and 7 are sectional views taken on the lines 4—4, 5—5, 6—6 and 7—7, respectively, of Fig. 1; and

Fig. 8 is a sectional view taken on the line 8—8 of Fig. 3

I claim:

The ornamental design for a fender for an automobile, substantially as shown.
